UNITED STATES PATENT OFFICE.

PERCY M. ELLIOTT, OF CHICAGO, ILLINOIS.

HANGER MECHANISM FOR CAR-DOORS.

1,276,738.

Specification of Letters Patent. Patented Aug. 27, 1918.

Application filed May 29, 1913. Serial No. 770,624.

To all whom it may concern:

Be it known that I, PERCY M. ELLIOTT, a citizen of the United States, and a resident of Chicago, county of Cook, and State of Illinois; have invented certain new and useful Improvements in Hanger Mechanism for Car-Doors, of which the following is a full, clear, and exact description.

The invention relates to sliding doors for railway cars and seeks to provide an improved track bar and guard whereby access of dirt and moisture through the upper portion of the door opening is effectively prevented. The invention consists in the features of improvement hereinafter set forth, illustrated in the accompanying drawings and more particularly pointed out in the appended claims.

Figure 1 is a side elevation of a portion 20 of a car body with the present improvement applied thereto. Fig. 2 is a detail section on the line 2—2 of Fig. 1.

The car body 10 is provided with an opening which is closed by a sliding door 11. One of the door posts 12 is shown in Fig. 25. As usual, a header 13 for the door opening extends between the upper ends of the door posts, and beneath the car plate 14. A track block 15 and a track bar 16 are 30 secured to the side of the car below the door opening by a series of bolts 17. Preferably the header 13 at the upper portion of the door opening projects outwardly to a slight extent over the upper edge of the door and the track block 15 abuts against this outwardly projecting portion of the header.

The outer, lower portion of the track block is recessed or cut away to receive the track bar 16. The latter comprises a vertical body portion or web which abuts against the outer face of the track block and through which the fastening bolts 17 extend. The lower portion of the main body or web of the track bar 16 extends downwardly 45 below the track block and is spaced from the outer edge of the header 13. The track bar is formed of rolled iron or steel and is provided with upper and lower track flanges 18 and 19 which project outwardly from the upper and lower edges of its web or main body portion. The track bar is also provided with a depending guard flange 20 which extends downwardly from the outer edge of the lower track flange and overlaps the upper edge of the door 11. A co-operating guard bar 21 is secured to the upper

edge of the door and is preferably in the form of a rolled metal Z-bar having a flange 22 depending from its outer edge and a flange 23 extending upwardly from its inner edge. The downturned flange 22 overlaps the outer face of the door and is secured thereto by bolts 24, and the upturned flange extends into the space between the header 13 and the lower part of the web or body 65 portion of the track bar 16.

It should be noted that in the preferred form shown, the track bar has Z-shaped portions 16, 19 and 20 which overlie and are substantially parallel to the corresponding parts of the Z-bar 21 and these parts are arranged closely adjacent and form a tortuous passage over the upper edge of the door to thereby effectively guard against the beating in of cinders and moisture 75 through the upper edge of the door opening.

The door is provided at its upper portion with a pair of hanger brackets 25 which are secured to its outer face. These brackets are provided with rabbeted portions 26 which fit over the lower edge of the flange 22 of the Z-bar and two of the bolts 24 extend through each of the brackets. The lower portions of the brackets abut against the outer face of the car and are secured thereto 85 by bolts 27. The upper portion 28 of each bracket is outwardly offset and extends upwardly outside of the depending flange 20 of the track bar. A roller 29 is mounted upon a stud or journal 30 extending inwardly from the upper end of each bracket and is held in place by a rivet 31 extending through the stud or journal, and having a washer 32 on its inner end overlapping the hub of the roller. The rollers are arranged 95 between the track flanges 18 and 19 of the bar 16 and normally, of course, rest upon the lower track flange 19. If the door is raised when it is shifted, the rollers engage the upper track flange to prevent rubbing 100 of the parts.

The upper face of the upper track flange 18 is downwardly and outwardly inclined to a slight extent, as shown in Fig. 2. The track block 15 is cut away or recessed to 105 snugly fit the inner face of the web or main body portion of the track bar and to project over and abut against the inner portion of the inclined upper face of the track flange 18. Preferably, as shown, the outer 110 face of the portion of the track block above the track bar is outwardly and downwardly

inclined. The arrangement is such that moisture is deflected outwardly by the upper inclined faces of the track block and track bar and cannot readily pass between the track block and bar. Even if moisture should find entrance between the track block and the bar, it will fall upon the guard bar 21, outside of its upturned flange 23, so that it cannot enter the door opening.

10 The construction is such that the upper edge of the door is most effectively guarded against the leaking or beating in of moisture and cinders over the upper edge of the door. At the same time, the parts are so 15 arranged that the door can be shifted without binding.

It is obvious that changes may be made in the details set forth without departure from the essentials of the invention defined in the 20 claims.

I claim as my invention:—

1. The combination with a car body having a door opening and a sliding door for closing said opening, of a rolled metal Z-shaped guard bar secured to and resting upon the upper edge of the door and having a depending flange overlying the outer face of the door and an upstanding flange projecting upwardly above the door opening, 30 said flanges extending the width of the door, a track bar secured to the car body above said door opening and having depending Z-shaped portions overlying and substantially parallel to the corresponding parts of 35 said Z-shaped guard bar, the lower horizontal member of said track bar being below the top of said guard bar, hangers secured to the door and extending upwardly outside of said track bar and having rollers 40 engaging the same, substantially as described.

2. The combination with a car body having a door opening and a sliding door for closing the same, of a rolled metal, channel-

bar track member secured to the side of the 45 car above the door opening and having the lower part of its vertical portion spaced from the adjacent part of the car, said member having upper and lower track flanges and a guard flange depending from the 50 lower track flange and overlying the upper portion of the door, hangers secured to the door and extending upwardly over said guard flange, rollers on said hangers arranged between said track flanges, and a 55 guard bar extending the width of the door and secured to and resting upon the upper edge of the door and having a flange at its rear edge extending upwardly behind said track member, substantially as described. 60

3. The combination of a car body having a door opening, a sliding door for closing said opening, said car having a track block secured thereto above said door opening and a header at the upper portion of the door opening projecting outwardly beneath said track block and over the upper edge of the door, a track bar secured to said track block and depending below the same to form a space between the vertical part of said track bar and said header, said bar having a track flange extending outwardly therefrom and a guard flange depending from said track flange and overlying the upper portion of 70 said door, a Z-shaped guard bar secured to 75 the upper edge of the door and having an outer depending flange overlapping and secured to the outer face of the door and an inner, upstanding flange extending into the recess between said track bar and header, 80 and hangers on the door having rollers engaging said track flange, substantially as described.

PERCY M. ELLIOTT.
